UNITED STATES PATENT OFFICE.

DAVID E. DARNELL, OF FULTON, TEXAS.

BALING-PRESS.

SPECIFICATION forming part of Letters Patent No. 787,082, dated April 11, 1905.

Application filed November 10, 1904. Serial No. 232,237.

To all whom it may concern:

Be it known that I, DAVID E. DARNELL, a citizen of the United States, residing at Fulton, in the county of Van Zandt and State of Texas, have invented a new and useful Baling-Press, of which the following is a specification.

This invention relates to presses for compressing hay, cotton, and other similar material into bales.

The invention has for its object to improve the construction and to facilitate the operation of this class of devices; and with these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a perspective view of a baling-press constructed in accordance with the principles of the invention. Fig. 2 is a vertical longitudinal sectional view of the same. Fig. 3 is a sectional detail view taken on the line 3-3 in Fig. 2. Fig. 4 is a plan view on a reduced scale, showing the press-box in the act of being reversed.

Corresponding parts in the several figures are indicated by like characters of reference.

The press-box 1 of the improved baling-press is supported upon a runner-frame composed of skids or runners 22, which are suitably connected at intervals by cross-bars 3, 4, 5, 6, and 7. The cross-bar 3, which is located at the front end of the runner-frame, supports an upright 8, the upper end of which is bifurcated and in which is pivotally mounted a lever 9. The cross-bar 5 supports an up-

wardly-extending shaft 10, the upper end of which is supported by an arm 11, extending from the upper end of the upright 8. Upon the shaft 10 is pivotally mounted the press-box 1, which is provided with separate compartments 12, 12. The front and rear sides of the compartments of the press-box are provided with slatted removable doors or closures 13, provided near their upper and lower ends with cross-strips 14 and 15, having projecting ends. The ends of the cross-strips 15 are adapted to engage recesses 16 in the framework of the press-box. The projecting ends of the strips 14 are adapted to be engaged by fastening devices 17, which are in the nature of rods provided at their ends thereof with cranks 18 and handles 19, whereby they may be readily adjusted in position to engage the projecting ends of the strips 14, thereby securing the doors or closures in position upon the press-box.

Hingedly connected with the upper end of the press-box at the outer side of each compartment is a platform 20, which may be folded down against the side of the press-box or which may, as shown in Fig. 1 of the drawings, be sustained in an elevated approximately horizontal position by means of a brace 21, hingedly connected with the side of the press-box.

The compartments of the press-box are separated by a partition 22, through which the supporting-shaft 10 extends. The press-box has a solid bottom 23, under which are secured supporting-planks 24 and 25, which are adapted to be supported, respectively, upon the cross-pieces 5 and 4 of the runner-frame. The shaft 10 extends through the central supporting-plank 24, as shown. Under the central supporting-plank is mounted a plate 26, having a depending yoke or bail 27, the arms of which extend through the cross-piece 5, which latter is provided with a metallic reinforcing-plate 28, perforated for passage of the arms of the yoke or bail. The plate 26 is not connected with the press-box; but it constitutes a spacing plate or washer which facilitates the turning of the press-box upon the shaft 10. Upon the under side of the cross-bar 4 of the frame adjacent to the

central cross-bar 5 is fulcrumed a lever 29, one end of which is pivotally connected with the yoke 27 and the other end of which is extended to the rear end of the runner-frame 5 and is there provided with a foot-piece or treadle 30. When the press-box is in normal operative position, the planks 25 25 upon the under side thereof are supported upon the cross-bars 4 4 of the runner-frame. By 10 pressing the treadle end of the lever 29 the press-box will be bodily lifted clear of the cross-bars 4 4 and 5 and may thus be conveniently and easily turned upon the central pivot formed by the shaft 10. The runner-frame 15 supports a suitable distance in rear of the press-box an upright 31, having at its upper end a cross-piece 32, with which is hingeedly connected a platform 33, the free end of which may be supported upon a cross-piece 34 of the press-box when the latter is in its 20 normal operative position, as shown in Fig. 1 of the drawings. When the press is to be turned, the platform 33 may be swung back to the position indicated in Figs. 2 and 4.

25 Pivottally connected with the operating-lever 9 is a rod 35, carrying a plunger or follower 36, adapted to enter the compartment of the press-box which is in alinement therewith when the press-box is in operative position. The plunger-rod 35 may be composed of a pair of side members 37, as shown in Fig. 1, said side members being provided with perforations 38 for the reception of a pin 39, whereby the plunger-rod is pivotally and adjustably connected with the press-lever 9. 30 The lever is provided near its rear end with a loop or staple 40, adapted to be connected with the operating-tackle, as will be presently described. The upright 8 is provided 35 with a pin or bracket 41, which when the plunger is elevated and lifted out of the press-box, as shown in Fig. 2, is adapted to temporarily support said plunger, as will be clearly seen in said figure.

40 45 The runner-frame is provided near its rear end with uprights 42, supporting a shaft 43, carrying a windlass 44. Said shaft is also provided with an operating-crank 45 and with a ratchet-wheel 46, engaged by a pawl 47, which 50 is pivotally connected with one of the uprights 42. Upon the windlass 44 is wound a flexible element, such as a rope 48, said rope being reeved over guide-pulleys 49 and through a block 50, to which latter the free 55 end of said rope is attached. The guide-pulleys 49 are supported in a bracket 51 upon the rear cross-bar 7 of the runner-frame, and the block 50 is provided with a hook 52, adapted to engage the loop or staple 40 upon the press-lever 9.

55 For the purpose of arresting and holding the press-box in proper operative position a spring-catch 53 is provided which may be attached to one of the runners of the frame. 60 Said spring-catch may be extended to form a

foot-piece 54 to enable it to be conveniently operated by the foot of the operator when the position of the press is to be reversed. The catch 53 is in the nature of a stop, and it cooperates with the platform 33 to retain the 70 press-box securely in position for operation, said platform when in engagement with the supporting-slat 34 serving to prevent movement of the press-box in the direction of itself, while movement of the press-box in the opposite direction is prevented by the catch or stop 53, which latter thus cooperates with the platform 33 in the manner and for the purpose set forth.

The runner-frame is provided at the front 80 end thereof with a clevis 55 for the attachment of draft when the press is to be moved from one place to another.

From the foregoing description, taken in connection with the drawings hereto annexed, 85 the operation and advantages of this invention will be readily understood by those skilled in the art to which it appertains. Assuming the press-box to be in proper operative position, as shown in Fig. 1, and one compartment thereof to be filled with material to be compressed, the plunger or follower is inserted in said compartment, the pawl 47 is disengaged from the ratchet-wheel 46, and sufficient rope is unwound from the windlass- 90 drum to enable the hook of the block 50 to be placed in engagement with the staple 40 of the press-lever. The pawl 47 is then replaced in engagement with the ratchet-wheel, and the windlass-shaft is rotated by the crank 45, 95 thus rewinding the rope and causing the lever to force the plunger into the proper compartment of the press-box, compressing the contents thereof. While this operation is taking place the other compartment of the 100 press-box will be filled with material to be compressed, the operator in charge of this part of the work occupying the platforms 33 and 20, to the former of which access may be had by a ladder 56, which also forms a 105 brace for the post or upright 31. The press-box during operation is retained stationary, partly by the spring-catch 53 and partly by the action of the platform 33, the free edge 110 of which is supported upon the cleat 34. 115 When the material in the press-box has been sufficiently compressed, the bale is tied. The press-lever is released from the tackle and thrown to the position indicated in Fig. 3, with the plunger supported upon the bracket 41. 120 The platforms 20, or the one of said platforms which in turning the press-box would be interfered with by the post or upright 8, will be folded down against the side of the press-box. The platform 33 is swung out of the way 125 to the position shown in Fig. 2. The press-box is slightly elevated by means of the foot-lever 29, and the spring-catch 53 is depressed, thus enabling the press-box to be bodily swung around upon the pivot formed by the shaft 10 130

until the compartment which has just been filled is brought into alinement with the plunger, at which point the press-box is automatically arrested by the spring-catch 3. The newly-formed bale is now removed by detaching the doors or closures 14, and a second bale is compressed in the manner just described while the empty compartment is being filled with material to be compressed.

This improved baling-press is simple in construction, easily operated with slight expenditure of power, durable, and not liable to get out of order. It is time-saving, owing to the fact that one compartment may be filled while a bale is being compressed in another compartment. The press may be readily removed from one place to another, and while being removed the press-box may be turned to a position in which it will not project beyond the side of the runner-frame, thus enabling the machine to pass through comparatively narrow gates and similar obstructions.

Having thus described the invention, what is claimed is—

1. In a baling-press, a supporting-frame, an upright shaft, a press-box mounted pivotally upon said shaft, and means for lifting the press-box clear from the supporting-frame while being turned upon the shaft.

2. In a baling-press, a supporting-frame, an upright shaft, a press-box mounted pivotally upon said shaft and having a plurality of compartments, a washer-plate engaging the under side of the press-box, and means for forcing said washer-plate in an upward direction to lift the press-box clear of the supporting-frame.

3. A supporting-frame, an upright shaft, a press-box pivotally engaging said shaft and having a plurality of compartments, a washer-plate engaging the under side of the press-box and having a yoke, and a suitably-supported foot-lever pivotally engaging said yoke.

4. A runner-frame having cross-bars and an upright shaft, a press-box pivotally engaging said shaft, normally supported upon the cross-bars and having a plurality of compartments, and means for lifting the press-box clear of the supporting-bars.

5. A runner-frame, a press-box pivotally

supported upon said frame and having a plurality of compartments, transverse cleats upon said press-box, a hingedly-supported platform adapted to be supported at its free edge upon a transverse cleat on one side of the press-box, 55 and a suitably-supported spring-catch engaging the opposite side of the press-box and cooperating with the platform to retain the press-box securely in position for operation.

6. A frame, a press-box having a plurality of compartments pivotally supported upon said frame, and a spring-catch disposed in the path of and adapted to arrest the rotation of the press-box, said spring-catch having a foot-piece. 60

7. A frame, an upright upon said frame, an upright shaft supported upon the frame, a bracket-arm connecting the upper end of said shaft with the upright, a press-box mounted for rotation upon said shaft and having a plurality of compartments, a lever connected pivotally with the upper end of the upright, a plunger having a rod pivotally connected with the lever, and supporting means for said plunger connected with the upper end of the up- 75 right. 70

8. A press-box mounted for rotation and having a plurality of compartments, an upright supported a distance from said press-box, a lever supported by said upright, a plunger having a rod pivotally connected with the lever, a windlass, suitably-guided tackle adapted to be wound upon said windlass, and a block connected with said tackle and adapted to be connected with the press-lever. 80

9. In a device of the class described, a press-box having detachable slatted closures provided with laterally-extended crossing strips, in combination with fastening members adapted to engage the extended ends of said strips, 90 said fastening members consisting of rods provided at the ends thereof with cranks having handles.

In testimony that I claim the foregoing as my own I have hereto affixed my signature in 95 the presence of two witnesses.

DAVID E. DARNELL.
